UNITED STATES PATENT OFFICE.

JOSEPH ARTHUR HENRY CASTONGUAY, OF BOSTON, MASSACHUSETTS.

COMBINED TOBACCO-BOX AND CIGARETTE-MAKER.

1,295,269.

Specification of Letters Patent.

Patented Feb. 25, 1919.

Application filed February 11, 1918. Serial No. 216,654.

To all whom it may concern:

Be it known that I, JOSEPH ARTHUR HENRY CASTONGUAY, a citizen of the United States of America, and a resident of Boston, in the 5 State of Massachusetts, have invented a certain new and useful Combined Tobacco-Box and Cigarette-Maker, of which the following is a specification, the same being a full, clear, and exact description of the invention, 10 such as will enable others skilled in the art to which it appertains to make and use the same.

This invention relates to an apparatus for 15 conveniently making small cigars consisting of finely cut tobacco rolled up in an envelop of thin paper—as rice paper—so as to form a cylinder open at each end, which device serves to form an attachment of a tobacco box of ordinary or approved construction, 20 the whole being of simple construction, inexpensive to manufacture and convenient and efficient in practical operation.

In order to attain the desired end the invention consists in the construction, arrangement and operation of parts hereinbelow set forth.

In the drawings, illustrative of one embodiment of the invention, Figure 1 represents a perspective view of an article constructed according to my invention; and Fig. 2 is a section taken through the upper part of the body of the same when in a closed relation.

Like numerals of reference indicate like 35 parts in both the views.

Referring particularly to the drawings, 1 denotes the body of a receptacle to hold tobacco and 2 a cover therefor which is in the present instance attached to the said 40 body by a hinge 3 as illustrated in Fig. 1.

My cigarette maker or former comprises two side walls 4 and an intermediate bottom portion 5, the side walls preferably being substantially of the same length as that of a cigarette wrapper and opened the width of a cigarette, the same being practically of U-shaped conformation. In the example illustrated the ends or projecting flanges of the former 4—5 are respectively passed over the 45 edge of the cover or closure 2, as at 6, and through the body of the cover as at 10.

The closure 2 of the receptacle 1 is preferably formed with a slot 7 and the trough-shaped cigarette former or container is constructed and arranged to be preferably attached to and detached from the lower face of the said closure in the present instance by means of one of the projecting flanges, as 6, at one end portion thereof being bent around the edge of the slot 7 of the closure, and the 55 projecting flange, as 10, at the other and opposite end portion of the cigarette former being passed through the body of the closure.

An orifice 8 may be formed in the closure, if desired, for the purpose of ejecting the 60 rolled cigarette from the former, and the receptacle may have means of suspension, as the spring catch 9.

In operation, the cigarette wrapper is 65 placed within the former and, after the insertion of the tobacco therein, the edges of the wrapper may be turned over on each other, and the completed cigarette may be pushed through the slot 7 or ejected from the former by means of the insertion of an 70 instrument through the orifice 8.

The spaces between the walls 4 of the cigarette former and the sides of the closure may serve as convenient receptacles to contain matches, if desired.

What I claim as my invention is:—

In a device of the class described, a receptacle, a closure therefor having a surrounding flange provided with a slot, and a cigarette former attached to the lower face of 80 the closure and comprising a trough-shaped container having projecting flanges at the end portions thereof, one flange being adapted to be passed through the body of the closure and the oppositely disposed flange being 85 constructed and arranged to be bent around an edge of the slot of the closure.

In testimony of the foregoing specification, I do hereby sign the same in the city of Boston, county of Suffolk and State of 90 Massachusetts, this 16th day of September, 1917.

JOSEPH ARTHUR HENRY CASTONGUAY.
